UNITED STATES PATENT OFFICE.

EBENEZER F. GRIFFITHS, OF PHILADELPHIA, PENNSYLVANIA.

PREPAYMENT GAS-METER.

SPECIFICATION forming part of Letters Patent No. 655,438, dated August 7, 1900.

Application filed December 13, 1899. Serial No. 740,152. (No model.)

To all whom it may concern:

Be it known that I, EBENEZER F. GRIFFITHS, a subject of the Queen of Great Britain, residing at Philadelphia, in the county of Philadelphia and State of Pennsylvania, have invented certain new and useful Improvements in Prepayment Gas-Meters; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to prepayment movements for gas-meters, and has particular reference to the valve that controls the flow of gas into the meter and to the mechanism that controls said valve.

The objects of my improvement are, first, to form the valve and its connections practically in one piece that can be easily and quickly soldered to the meter in a position that will allow of the free movement of said valve, and, second, to provide mechanism that will at the proper time quickly open wide or tightly close the valve.

The general construction of the meter and the special mechanism designed to give movement to the valve-operating device are fully described in the patent granted to me on April 26, 1898, No. 603,079. I have therefore not shown or described these parts in all of their detail; but to more easily distinguish the old from the new I have marked the old parts with the same letters that were used to designate them in the former patent and used numerals to designate the new parts in this application.

In the accompanying drawings, Figure 1 is a vertical sectional view of the valve, showing the valve-operating mechanism connected therewith. Fig. 2 is an elevation of the valve-operating device disconnected from the other parts of the meter. Fig. 3 is a transverse sectional view of the mechanism shown in Fig. 1, as on line xx of said figure.

A is the outer casing or body of the meter, and A' is the gas-inlet pipe.

A² is the gas-outlet pipe, connected with the house-pipes, and B is a coin-box attached to

the side of the meter and containing the coin-operated mechanism.

1 is a tubular case or inclosure surrounding the valve through which the gas is admitted into the meter. 55

2 is an opening in one side of the tubular case 1, through which opening the gas is admitted from the inlet-pipe A', flowing in the direction indicated by the arrows through the short pipe a' and the slanting pipe or passageway 3, that extends from the opening 2 in the side of the valve-casing to the opening 4 in the short pipe a'. 65

a² is a puppet-valve located in the bottom part of the tubular case 1, which has formed therein a suitable valve-seat. The tubular case 1, containing the valve a², is provided with a bottom flanged portion 5, and it is secured in the meter immediately over an opening in the gas-outlet pipe A². 70

a³ is the stem of the valve. This valve-stem is pivotally connected by a pin 6 to the lever 7, which has at one end the slot 8 and at the opposite end the slot 9. 75

10 is a post supporting one end of the slotted lever 7 and provided with a suitable pin 11, fitting into the slot 8 on the end of the lever. 80

12 is a top having therein a stuffing-box screw-threaded on the outside and fitting into a corresponding screw-thread on the top portion of the valve-casing 1. The valve-stem a³ passes through openings in the top and bottom of the stuffing-box, and as these top and bottom openings are some distance apart and register with each other an easy straight up-and-down movement can be readily imparted to the valve. 85

13 is a lever pivoted at 14 and having one of its ends extending into the slot 7 on the end of the valve-lifting lever 9, the under side of the forward part of which lever is provided with a downwardly-projecting spur 15, 95 the bottom of which slides on the periphery of the disk 16 and fits into the notch 17 when the valve is closed. The forward side or edge of this downwardly-projecting spur 15 is beveled and a corresponding bevel formed on the forward side of the notch 17 in the disk 16, so that when the valve is closed and the disk is in the position shown in Fig. 1, with the spur 15 fitting into the notch 17, a movement 100

of the disk in the direction indicated by the arrow will force the inclined surface of the spur 15 to slide over the incline in the notch 17 and quickly force the forward end of the lever 13 upward, thus opening the valve a^2 and allowing the gas to flow through the valve. The bottom of the spur 15 sliding along on the periphery of the disk 16 (see Fig. 2) the valve is kept wide open until a reverse movement of the mechanism forces the spur 15 down into the notch 17.

18 is an arm or extension on the disk 16. The end of this arm when the disk is turned toward the right hand slides over the bottom edge of the wide end portion of the pivoted lever 13, operating said lever so as to depress the forward end thereof, and thus through the lever 7 close the valve a^2 . The disk 16 is secured upon the end of the shaft d^2 , that carries a pinion d^3 , that fits into and is operated by the cylindrical rack d' , that is moved back and forward by the screw-threaded shaft c , that is in turn operated by the worm-wheel c^3 , that engages with the worm d^4 on the shaft a^7 .

The valve a^2 and the stuffing-box 12, being attached to the tubular casing 1, they all together practically form one piece, so that when they are ready to be set in position they require no adjustment in relation to each other, it being only necessary to fit the bottom flanged portion of the tubular valve-casing 1 into the opening that registers with the opening in the pipe A^2 . The portion of the meter upon which the valve and its connections are placed being only the thickness of a sheet of tin, the short flanged portion of the casing 1 will project through and a secure solder-joint can readily be made. This construction and arrangement of the valve makes a strong and reliable device that requires no special skill to set in place and is not likely to get out of order. Should the valve get out of order, it is only necessary to remove the pin 6, that connects the valve-stem to the lever 7, slide said lever forward or backward, and remove it from its place, when the valve and stuffing-box can be removed either separately or both together. The disk 16, being provided with the comparatively-long arm 18, that operates against the short arm of the lever 14, a quick and positive movement is

imparted to the long end of said lever and through it to the lever 7, lifting the valve a^2 from its seat, so that it is full open almost as soon as it has been moved at all. The valve-lifting lever 7 having open slots on both ends, no nice adjustment is required, and when any repairs are necessary it can easily be disconnected from the other parts.

Having thus described my invention, what I claim as new, and desire to secure by Letters Patent of the United States, is—

1. A valve-lifting mechanism for prepayment gas-meters, consisting of the disk 16, having therein the beveled-edge notch 17, and provided with the extending arm 18, the lever 13, having thereon the downwardly-projecting slanting-edge spur 15, adapted to slide over the periphery of the disk 16, and fit into the notch 17, the forward end of said lever being connected with a suitable valve and the rear end adapted to be operated by the arm 18, substantially as shown.

2. In a prepayment gas-meter, the combination of the disk 16, connected to suitable operating mechanism and having thereon the beveled-edge notch 17, and extending arm 18, with the lever 13, having thereon the downwardly-projecting slanting-edge spur 15, one end of said lever being adapted to be operated by the arm 18, and the opposite end fitting into the lever 7, connected with a valve controlling the flow of gas through the meter, substantially as shown.

3. In a prepayment gas-meter, the combination of the disk 16, connected to suitable operating mechanism and having therein the beveled-edge notch 17, and extending arm 18, the pivoted lever 13, having thereon the spur 15, slotted lever 7, one end of which is connected with the lever 13, and the opposite end fitted to the post 10, with the casing 1, having therein the valve a^2 , the stem of which is connected to the lever 7, and a stuffing-box, all arranged, substantially as shown and for the purpose described.

In testimony whereof I affix my signature in presence of two witnesses.

EBENEZER F. GRIFFITHS.
